UNITED STATES PATENT OFFICE.

GEORGE GOUDIS, OF DETROIT, MICHIGAN.

MEANS FOR UNCURLING FILMS OR STRIPS.

1,385,537.

Specification of Letters Patent. Patented July 26, 1921.

Application filed January 15, 1921. Serial No. 437,558.

To all whom it may concern:

Be it known that I, GEORGE GOUDIS, a subject of the King of Greece, residing at Detroit, in the county of Wayne and State of Michigan, have invented certain new and useful Improvements in Means for Uncurling Films or Strips, of which the following is a specification, reference being had to the accompanying drawings.

10 This invention relates to means for treating or coating sensitized films such as used for photography, or for treating photographic strips, paper, or the like, and particularly to means for flattening or uncurling the film or strip after it has been sensitized.

In the preparation of sensitized gelatin films, the unsensitized film passes to a sensitizing bath and is carried around a roller in this bath and then is carried through a drier which is a relatively long housing open at its opposite ends, one part of the housing having means whereby cold air is admitted to the housing and the other part of the housing having means whereby warm air is admitted thereto to thus dry the film without causing the film or the emulsion thereon to crack. The film is carried through this housing on a carrier and is then carried to a reel. The film as it dries contracts upon the upper or sensitized surface, and as a consequence the film rolls up or curls up at its lateral edges and the services of an operator are required to unfold or uncurl this film as it passes from the drier so that the film may be wound upon a reel and be relatively flat transversely.

The object of my invention is to provide means of this character which will not injure in any way the sensitized coating on the film and which will prevent the film from cracking or folding.

A further object is to provide a device of this character comprising two rollers convergently disposed and having the vertex of the angle made by the rollers extending toward the oncoming film so that the convergent ends of the rollers will be inserted within the curled film and as the film is advanced the rollers will act to spread the film laterally or uncurl it so that the film is then

placed in condition to be wound upon a reel.

Other objects will appear in the course of the following description.

55 My invention is illustrated in the accompanying drawings, wherein:

Figure 1 is a diagrammatic view partially in section showing an apparatus for coating films with sensitized emulsion and showing 60 my device applied thereto;

Fig. 2 is a top plan view of a portion of the apparatus showing my device in applied position and acting to uncurl a film;

Fig. 3 is a section on the line 3—3 of 65 Fig. 2;

Fig. 4 is a section on the line 4—4 of Fig. 2.

Referring to Fig. 1, wherein the mechanism for sensitizing and drying the film is 70 diagrammatically shown, B designates a bath of sensitized material over which the film A passes. This passes from a reel 10. The film is caused to come in contact with the sensitizing liquid in the bath by means 75 of a roller 11. From the roller 11 the film passes upward and enters a longitudinally extending housing or chamber 12 which is open at opposite ends and which, under ordinary circumstances, is approximately 200' in 80 length.

Disposed within this chamber is the upper flight of an endless carrier 13. This endless carrier extends through the chamber and is carried on its ends by rollers 14, and the 85 lower flight of the carrier depends below the chamber. This endless carrier may be of any suitable or usual construction and engages with the under or unsensitized side faces of the film and draws the film 90 gradually through the drying chamber 12. After it passes through the drying chamber, the film passes over suitable guides 15 and is carried to a winding roller 16. As the film passes through the housing 12, it is submitted first to the action of cool air and later to the action of warm air so as to dry the coating on the film. It is necessary to do this in order to prevent the emulsion on the surface of the film from cracking, which 100 it would do if this film with its coating of wet emulsion were submitted to the action

2
of hot air first and too sudden a drying action was secured.

To this end, the housing 12 has a cold air inlet pipe 17 entering it adjacent its inlet end and a warm air inlet pipe 18 entering it more or less adjacent its exit end so that for the first part of the passage through the housing 12 the film is submitted to the action of cool air and for the second part of its 10 passage it is submitted to the action of warm air. All of these parts are such as are commonly found in film sensitizing mechanism and form no part of this invention.

As before remarked, the film as it passes 15 through the drier housing 12 and is carried along through this housing by the endless carrier 13 gradually commences to contract upon its upper or sensitized face as the sensitizing coating dries and must be spread or 20 flattened out so as to be transversely flattened before it reaches the guides 15 and the roller 16. The degree of curvature, curl or roll which the film takes varies. Sometimes the roll is relatively tight, sometimes it is 25 relatively open, but for the purpose of opening the film and uncurling it, I dispose below the path of travel of the film at the exit end of the housing 12 a platform 19 and dispose above the path of travel of the film a trans- 30 verse bar 20 having bearing brackets 21 at- tached thereto, these brackets being disposed in angular relation to each other and to the bar 20. Beyond the transverse bar 20 I mount the transversely extending shaft 23 carrying the band wheel 24 or other means 35 whereby power may be transmitted to this shaft, and I mount upon this transverse shaft the beveled gear wheels 25. Mounted in the bearings 21 at their rear ends and in suit- 40 able bearings at their forward ends are the angularly disposed shafts 26 carrying the rollers 27 and the beveled gear wheels 28 which mesh with the beveled gear wheels 25. These rollers 27 rotate with the shafts 26 45 and extend convergently so that the adjacent ends of the shafts 26 and rollers 27 are relatively close together and disposed at the middle of the film A which is moving in the direction of the arrow in Fig. 2.

50 The transversely curved or curled film moves as described in the direction of the arrow in Fig. 2 and the upwardly curved edges of the film or strip A strike the rollers and as these rollers are rotating in the direc- 55 tions of the arrows in Fig. 2, that is in a direction generally reverse to the line of movement of the film A, it is obvious that these rollers will act to spread the film laterally and to gradually flatten out the film so that by the time the film has reached the forward portion of the rollers, the film has become only slightly curved, as illustrated in Fig. 4. This slight curvature of the film is of no importance. It will be seen that these rollers touch the edges of the film and do not touch

the face of the film. Of course, while some curvature will remain in the film, this is of no importance and is taken out when the film is wound upon the rollers 16. It is obvious that a series of these rollers 27 may 70 be disposed along the path of travel of the film, each one acting to further flatten the film, and I do not wish to be limited to the use of one pair of rollers 27 or to a plurality of pairs. Neither do I wish to be limited 75 to the exact manner of mounting the rollers 27, nor the manner of driving these rolls, though I have found this very efficient for the purpose described. After the film has passed the rollers 27 and the platform 19, 80 it passes over the roller 15 and into suitable or usual guides whereby the film is carried to the winding roller 16.

My construction obviates entirely the liability of the film becoming folded over upon 85 its edges. If a fixed spreading device were used in place of the roller 27, there would be a liability of the film being flattened but with its margins turned inward, and these margins would tend to become folded down 90 flat upon the film as it passes through the guides. By having the rollers 27 rotate in a direction reverse to the general direction of the film, the contact of the rotating rollers with the film acts to spread the film laterally 95 and not merely flatten it down, that is draw the film laterally from its middle, so as to take the curl out of it. This mechanism does away with the necessity of an operator standing at the discharge end of the heater 12 and flattening the film or taking the curl out of it as it leaves the heater. 100

While I have referred to this device as being particularly designed for use in flattening out the gelatin photographic films, I 105 wish it understood that it might be used for flattening out any film or strip, whether made of gelatin paper or any other substance which is liable to curl up and which travels longitudinally. 110

I claim:—

1. The combination with means for applying a coating to a film and a drier for the film through which the film is carried, of means for flattening the film transversely comprising flattening members disposed in the path of travel of the film and converging toward each other in the direction from which the film is moving. 115

2. The combination with means for applying a coating to a film and a drier for the film through which the film is carried, of means for flattening the film transversely comprising convergently disposed, rotatable, flattening rollers disposed in the path 120 of travel of the film and converging toward each other in the direction from which the film is moving. 125

3. The combination with means for applying a coating to a film and a drier for the 130

- film through which the film is carried, of means for flattening the film transversely comprising convergently disposed, rotatable, flattening rollers disposed in the path of travel of the film and converging toward each other in the direction from which the film is moving, and means for rotating said rollers reversely to the movement of the film.
- 10 4. The combination with means for sensitizing a film and a drier casing through which said film is carried, of means for flattening the film comprising a platform over which the film passes, rollers mounted 15 above the platform to contact with the edges of the film, said rollers converging toward the direction from which the film is moving, and means for rotating said rollers reversely to each other and reversely to the direction 20 of movement of the film.
5. The combination with means for sensitizing film and a drier casing through which said film is carried, of means for flattening the film comprising a platform over 25 which the film passes, rollers mounted above the platform to contact with the edges of the film, said rollers converging toward the direction from which the film is moving, beveled gear wheels operatively connected 30 to the rollers to rotate them, a transverse driving shaft, and beveled gear wheels mounted upon the shaft engaging the beveled gear wheels on the rollers, the driving shaft being rotated in a direction to cause
- the rotation of the rollers reversely to each other and to the direction of movement of the film.
6. The combination with a film coating bath, a drier housing into which the film is carried from the bath, an endless conveyer 40 mounted in the drier housing and by which the film is carried through the housing and means for supplying cold and hot air to the housing, of means at the discharge end of the housing for flattening the film including a pair of power driven rollers arranged in convergent relation and at an inclination to the path of travel of the film, said rollers converging toward the direction from which the film is moving and the divergent 45 ends of the rollers extending beyond the margins of the film.
7. In a mechanism of the character described, the combination with a platform and means for causing a film to travel longitudinally over said platform, of means for flattening the film comprising a pair of power driven rollers convergently disposed with relation to each other in the direction from which the film is moving, the convergent ends of the rollers being disposed approximately in line with the middle portion of the film, the divergent ends of the rollers being disposed beyond the side edges of the film.
